UNITED STATES PATENT OFFICE.

HORACE G. HANCOCK, OF NEW BRITAIN, CONNECTICUT, ASSIGNOR TO NORTH & JUDD
MANUFACTURING COMPANY, OF NEW BRITAIN, CONNECTICUT.

SNAP HOOK.

Application filed May 21, 1924. Serial No. 714,932.

To all whom it may concern:

Be it known that I, HORACE G. HANCOCK, a citizen of the United States, and resident of New Britain, in the county of Hartford 5 and State of Connecticut, have invented certain new and useful Improvements in Snap Hooks; and I do hereby declare the following to be a full, clear, and exact description of the invention, such as will enable others skilled in the art to which it appertains to 10 make and use the same.

The object of this invention is to provide a snap hook of neat appearance which can be produced very cheaply without any loss 15 of efficiency, and in which the spring will be held firmly in place without the use of any lugs, pins or other elements extending across or over its inner surface or bight. The invention is illustrated in the accompanying 20 drawing and consists in certain novel features which will be hereinafter first fully described and then more particularly pointed out in the appended claims.

In the drawing, Figure 1 is a top plan 25 view of my improved snap hook;

Figure 2 is a bottom plan view of the same;

Figures 3 and 4 are longitudinal sections 30 showing successive steps in the manufacturing process.

The body 1 of the hook terminates at one end in a bill 2 and at its opposite end in a transverse strap eye or loop 3 of any preferred form, being a single integral structure of malleable iron, cast brass or other metal which may be bent somewhat in the process of manufacture. The butt end of the body rises from the loop 3, as shown at 4, and is in the form of an arcuate web bending 35 forwardly and terminating at its forward end or edge in a pendent lip 5 while its rear or lower end or edge initially extends downwardly or rearwardly as a substantially straight rib or tooth 6, as shown in Fig. 3. In advance of the web 4, a longitudinal slot 7 is formed through the body, the front end wall 8 of the slot being inclined 40 downwardly from front to rear and being formed at its lower rear end with a transverse bead or rib 9 and a transverse 45 groove or seat 10 immediately in advance of the rib or bead. The end of the bill 2 is widened somewhat and is formed with a recess or seat 11 in its under side to be engaged

by the free end of the spring tongue 12. 55 The tongue is formed from a strip of resilient or spring-tempered metal which is doubled on itself to form the tongue and a basal or attaching arm 13 of less length than the tongue. The bend or bight 14 of the 60 spring is adapted to seat closely against the web 4 and a kink 15 is formed in the spring at the base of the tongue to be engaged by the lip 5. The arm 13 has its terminal bent transversely to define the opposed kinks 16 65 and 17 adapted to seat respectively over the bead 9 and in the groove 10.

In assembling the spring with the body, the bight or bend 14 is inserted through the upper mouth of the slot 7 and positioned 70 against the web 4 with the kink 15 engaged with the lip 5, the tongue being sprung into engagement with the seat 11 and the kinks 16 and 17 being properly seated as shown in Figures 3 and 4. After the spring has been 75 thus fitted in place, the tooth 6 is bent forward as shown in Figure 4 so that the entire bight or bend of the spring will be supported and braced, the tooth being substantially flush with the arm 13 and the side 80 walls of the slot 7 constituting cheeks which engage the edges of the spring and prevent sidewise movement of the same. When the tooth 6 is bent forward as described, the spring becomes locked in place without any 85 extraneous fastening devices or any fulcrum elements being inserted across it or over its edges from the side walls of the slot, and a cheap but neat and efficient snap hook is 90 produced.

Having fully described my invention what I claim as new and desire to secure by Letters Patent, is:—

1. A snap hook comprising a body having a web closing its back end, and having an inset front face and a tongue consisting solely of a doubled spring strip having its entire bight snugly seated against and held by the inset front face of said web. 95

2. A snap hook comprising a body having a longitudinal slot and a bendable web constituting the rear end wall of the slot, and closing the back end of the body and a tongue consisting solely of a spring strip doubled on itself with its bight inserted into the slot and the entire extent of the bight snugly seated against and supported by the front face of said web, the branches of the 100 105

spring being lockingly engaged with the body at the upper front end of the web and the lower end of the front wall of the slot.

3. A snap hook comprising a body having a web constituting its back end, said web having a concave front face, a transverse in-turned lip at the upper forward end of said web, the body having a longitudinal slot in front of the web, a transverse bead at the 10 lower end of the front wall of the slot and a transverse groove in said wall immediately in front of said bead, and a tongue consisting of a spring strip doubled on itself and having its bight seated snugly in the con-

cave face of said web, there being a transverse kink in the upper branch of the spring to be engaged by said transverse in-turned lip, and the lower branch of the spring terminating in reverse bends engaging over said bead and in said groove respectively. 15

In testimony whereof, I have signed this specification in the presence of two subscribing witnesses. 20

HORACE G. HANCOCK.
